INVENTOR

John T. Cassidy,

BY Drake & Co. ATT'YS.

UNITED STATES PATENT OFFICE.

JOHN T. CASSIDY, OF NEWARK, NEW JERSEY.

BUTTON-MACHINE.

SPECIFICATION forming part of Letters Patent No. 367,501, dated August 2, 1887.

Application filed April 16, 1887. Serial No. 234,991. (No model.)

To all whom it may concern:

Be it known that I, JOHN T. CASSIDY, a citizen of the United States, residing at Newark, in the county of Essex and State of New Jersey, have invented certain new and useful Improvements in Button-Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figure 1 represents a side elevation of a button-machine embodying my improvements; and Figs. 2, 3, and 4 are detail views of the same.

The object of the invention is to overcome certain objections urged against machines of this class heretofore in use, to facilitate the manufacture of buttons, and to make a more perfect article.

In referring to the drawings, A and B, Figs. 1 and 2, represent, respectively, a suitable frame and base or bed plate, the latter being adapted to receive and support a rotating plate, C, provided with a series of receptacles, D, which carry a series of dies or shapers, D', of different sizes, as indicated in Figs. 1 and 2. Said dies and receptacles are of varying sizes, corresponding with the sizes of the buttons, as will be understood. Operated by a suitable lever, E, is a vertically-moving plunger, F, Fig. 1, carrying a removable upper die or former, G, the bottom end of which is recessed and provided with a central projection, c', by means of which the metal back or shell of the button is pressed or closed tightly down upon the back part of said button and clinched or fastened thereon, completing and finishing the same in one operation. Adjusted upon the bottom end of said upper die or former is a vertically-moving cutter or crimper, c', which moves vertically upon said plunger, being limited in its motion by a stop-pin, p, projecting through a slot, p', Figs. 1 and 4. Said crimpers and dies vary in size, according to the size of the buttons. (Usually there are three sizes.) Said cutters or crimpers serve to cut and afterward to turn or fold the cloth beneath the said metal back or shell before

the latter is pressed home and fastened, as above stated, and as will be hereinafter more particularly described. The bottom edge of said crimper is in its normal condition, say, 55 one-quarter of an inch (more or less) below the end of the upper die, it being held thereat by a spring, s, Fig. 1, so that when the plunger is operated the crimper first comes in contact with the cloth blank or cover which has been 60 laid on top of one of the receptacles D and the button-mold placed thereon and pressed by the finger into the cavity upon the die or shaper D', and the back or shell placed in position, and as the pressure on the plunger is increased 65 forces the upturned cloth inward beneath the shell, and at the same time the central projection, c', on the upper die engages the inside of the hub on the button-mold and spreads and clinches the same over upon said back or shell, 70 firmly fastening the same and completing the operation in one motion.

When the pressure upon the lever is released, a lever, R, Fig. 1, is pressed downward, and the short arm thereof engages with said 75 die or shaper at the bottom and presses the same upward, thereby throwing the button out of the cavity, as will be understood by referring to said Fig. 1.

The rotating plate C, above referred to, is 80 provided with notches n, each of which engages in turn with a spring-pawl, o, when turned in the requisite position to enable the crimper c' to engage the receptacles, as will be understood by reference to Figs. 1 and 2. 85

The operation of the device is as follows: The cloth blank is laid over one of the receptacles above the anvil or shaper and the button-mold laid on top of the cloth and by the thumb or finger pressed down into the cavity 90 on the top of the die or shaper, which operation curls the cloth upward around the outer rim or periphery of the mold. The metal back or shell is then laid on top of the cloth and the plunger brought down by means of the lever, 95 whereupon the crimper, first coming in contact with the upturned edge of the cloth, on the outer side thereof, presses it down on the button-mold, and as the crimper recedes the upper die comes in contact with the back or shell 100 and the central portion or spreader of said die engages with the hollow hub of the button-

mold on the inside thereof, thereby pressing the back firmly down upon the cloth and clinching said hub over upon the central part of said back at the same time, thereby finishing 5 the operation at one stroke of the lever. On releasing the lever the finished button is thrown from the machine by means of the lever R, which engages with the button die or shaper at the bottom, as above stated.

Having thus described my invention, what I claim as new is—

1. The combination, in a button machine, of a rotating plate provided with receptacles, as D, anvils or shapers, as D', fitting in said receptacles, as shown, a vertically-movable plunger, as F, an upper die, as G, adjusted upon said plunger, and a cutter or crimper, as e', working on said upper die, said parts being arranged and adapted to operate substantially 15 as and for the purposes set forth.

2. The combination, in a button-machine, of a rotating plate, as C, having receptacles therein, carrying a die or shaper, as D', and a lever, as R, adapted to operate said dies, as and for the purposes set forth.

3. The combination, in a button-machine, of a vertically-movable plunger, as F, an upper die, as G, adjusted thereon, a cutter or crimper, as e', adjusted and movable on said die G, a spring, as s, and means, as p and p', for limiting 30 the movement of said crimper, said parts being arranged and adapted to operate substantially as and for the purposes set forth.

In testimony that I claim the foregoing I have hereunto set my hand this 28th day of 35 March, 1887.

JOHN T. CASSIDY.
